UNITED STATES PATENT OFFICE

LESLIE SALTER, OF VALLEJO, CALIFORNIA

PONTOON DIVER

Application filed May 15, 1929. Serial No. 363,333.

The present invention relates to improvements in means for raising submerged boats, such as submarines or even larger boats, that have met with an accident, and the 5 principal object of the invention is to provide a means of the character described which allows the boat to be raised in a single operation that may be performed possibly within a few hours so that the lives of the occupants 10 of the submerged boat may be saved.

A further object of the invention is to combine all of the elements necessary for the raising of the boat into a single floating unit that may be positioned on the surface of the 15 water above the boat to be raised and may then be lowered to be brought into operative relation relative to the submerged boat for gripping the same and for raising it to the top.

20 A further object of the invention is to provide a guide means for the floating unit by means of which it will be guided while it is being lowered so that it will always assume the correct position relative to the boat to be 25 raised.

A further object of the invention is to provide, in combination with said floating unit, gripping members which may be made to straddle the boat while the float is swinging 30 into operative position and to close upon the boat for gripping the same after the floating unit has been lowered so that when the latter is raised the boat will be raised with the floating unit.

35 It is further proposed in the present invention to use the principle of the pontoon for lowering and raising the floating unit, the pontoons being filled with water for the purpose of lowering the float, and means being 40 provided for driving out the water when it is desired to raise the floating unit.

Other objects and advantages of my invention will appear as the specification proceeds.

45 The preferred forms of my invention are illustrated in the accompanying drawings, in which

Figure 1 shows a side elevation of my boat- 50 raising means as the same is positioned above

a submerged boat at the beginning of the operation,

Figure 2 shows the floating unit as encircling the boat;

Figure 3 shows a plan view of the float 55 encircling the boat to be raised,

Figure 4 is an enlarged sectional view taken along the line 4—4 of Figure 3,

Figure 5 is a horizontal section taken along the line 5—5 of Figure 4,

Figure 6 is a vertical section showing a 60 modified form of gripping means,

Figure 7 is a vertical section taken along the line 7—7 of Figure 6.

While I have shown only the preferred 65 forms of my invention, I wish to have it understood that various changes or modifications may be made within the scope of the claims hereto attached without departing 70 from the spirit of the invention.

In the form shown in Figures 1 to 5, I provide a huge floating body 1 which may be made of any suitable shape and is preferably constructed in such a manner as to leave a large inner opening or well indicated at 2 75 of such proportions that the boat to be raised, which is indicated at 3, may be encircled by the floating unit.

This unit may be made in the form of a 80 frame or in the form of a shell so that the entire unit would form a single pontoon. It may, however, be provided with a number of individual pontoons indicated at 4, and in the latter case no attention need be paid to making the floating unit water-tight; in fact, 85 side plates may be done away with altogether, and the individual pontoons 4 supported in a strong frame only. Suitable means are provided in a flexible hose 5 for admitting a pressure medium into the pontoons 90 for driving the water out of the same, and suitable discharge ports for the water are indicated at 6. The structural features of the pontoons are conventional in character and form no part of the present invention. 95

Within the well there are supported on strong cross members 7 a suitable number of gripping jaws adapted to encircle the boat to be raised and to lift the same when the float rises. Each set of gripping elements 100

consists of three jaws 10 pivoted on a longitudinal shaft 8 supported in one of the frame members 7, one jaw being made to engage the boat from one side and the other two jaws being made to straddle the first jaw and to engage the boat from the opposite side. The lower ends of the jaws, below the pivot 8, are made to substantially conform to the shape of the boat to be lifted. The jaws terminate at the bottom in pointed ends shown at 11 and these pointed ends are adapted to be pushed through the mud and are formed with shoulders 12 near the pointed ends for engaging with the duct keel 13 of the boat to be raised from opposite sides so that after engagement it is impossible for the jaws to lose their hold. Water jets 11' may be provided at the points of the jaws for facilitating movement through clay and may be fed through pipes not shown in the drawing.

For locking the three jaws in their boat-gripping position, I provide the bridging member 14 pivoted to the single jaw as shown at 15 and held in a substantially horizontal position by means of a pin 16. The free end of this bridging member is tapered as shown at 17 and strikes a pin 18 supported between the opposing jaws when the jaws grip the boat. Back of the tapered point of the bridging member 14 is provided a groove 19 which allows the bridging member 14 to drop after the taper has passed the pin 18 and to become locked in the groove. A cable 20 may be provided for lifting the bridge 14 to allow the jaws to be opened.

To prevent the boat from rocking within the jaws, suitable wedge blocks may be slidably mounted on the inner faces of the frame for operation from above by means of chains or the like. The upper ends of the jaws are interconnected by means of a cylinder 21 pivoted between the double jaws and a connecting rod 22 pivoted to the single jaw and having a piston 23 riding in the cylinder. Suitable means are provided in the tubes 24 and 25 for admitting air under pressure through the cylinder from opposite sides whereby the jaws may be pushed apart or drawn together respectively. It should be understood that any other suitable means might be used for the purpose of operating the jaws, and that particularly hydraulic means might be found well adapted for this purpose.

For centering the floating unit relative to the boat submerged in the water, I preferably use buoys 26 connected with the front and the stern of the boat through ropes or cables 27. Buoys of this character are provided on submarines at the present time, and the position of the boat may be ascertained thereby. My floating unit is first arranged relative to the boat so that two buoys 26 would be confined within the well of the floating unit, which would indicate that the floating unit lies di-

rectly over the boat and that if sunk in a straight line it will encircle the boat.

For guiding the float, I provide a number of chains 28, preferably four, one in front and one in the rear and two on the sides. These chains are suitably wound on winches 29 and pass through hawse pipes 30 passing vertically through the float. They have anchors 31 preferably of the mushroom type secured to their lower ends, and I provide a number of buoys that may be fastened to their upper ends after a desired amount of chain has been unreeled.

My invention as thus far described operates as follows. As soon as news of the accident which caused the submarine or other boat to sink to the bottom of the sea has reached the operator of one of my units, he will proceed to tow the unit to the place where the accident happened, it being understood, of course, that the device is towed and that the operator remains on the tugboat while the actual operation is performed. The operator finds the buoys 26 by means of which he locates the submarine and then tows the float in place so that the buoys 26 are confined within the well, which indicates that the float lies directly over the submerged boat in such a manner that if sunk the float will encircle the boat. Next the anchors 31 are dropped by unreeling the winches 29 until the anchors reach a place the same distance above the bottom of the sea as the surface of the float is above the surface of the sea. When the anchors are in this position, which is indicated in full lines in Figure 1, each chain is separated from its winch and attached to a buoy shown at 32. Next the float is lowered by letting water into the pontoons, care being taken that at this time the jaws are in open position so as to clear the boat on opposite sides when the float sinks. While the float slowly submerges, the anchors 31 keep sinking with the float until the surface of the float reaches the level of the water, at which time the anchors are firmly inbedded in the bottom of the sea. As the float sinks still further, the buoys 32 take the load of the anchor chains so that the latter are held taut between the buoys and the anchors and serve as a guide means for the descending float. The buoys are partially filled with water so that if the chains are not taut enough the water can be blown out with air. It should be particularly observed that even if the float should drift slightly due to a slight drifting of the buoys, by the time it descends toward the bottom it will reach the correct position due to the fact that the anchors cannot move under the influence of ocean currents.

Thus the float assumes a position in which it encircles the sunken boat approximately as shown in Figure 4. It will be seen from this figure that as the bottom of the float

reaches the bottom of the water, the points of the jaws are substantially on a level with the bottom of the float and that the operation of the jaws will cause the latter to work through the mud and to reach a depth substantially below the bottom of the float so as to be sure to get below the bottom of the boat even if the latter has dug itself into the bottom of the sea.

10 Next, the operator causes air to enter into the cylinder 21 whereby the upper ends of the jaws are pulled together and the lower ends are brought together into gripping engagement with the bottom of the boat to be lifted. When the end position is reached, the jaws are firmly locked by the bridging member 14.

Now the operator is ready to lift the boat. He forces air into the pontoons whereby the water is driven out of the same and whereby the combined weight of the float and the boat is reduced so as to be less than that of the amount of water displaced by their combined volumes when the entire unit will 25 gradually rise to the surface of the water and thence may be towed to any place desired, preferably to a drydock.

In the form shown in Figures 6 and 7, a different operating means is provided for 30 the jaws 10, the same comprising a transverse rod 33 suitably supported in the float and formed with opposite threads 34 on which nuts 36 are made to ride, the nuts being pivoted to the jaws as shown at 38. The rod 34 has a central pinion 39 thereon which meshes with a gear wheel 41 adapted to be rotated by any suitable power indicated at 42. It will be seen that when the gear wheel 41 revolves, rotary motion is imparted 40 through the pinion 39 to the rod 33, which causes the nuts 36 to be moved inwardly or outwardly, as the case may be, for separating or drawing together the jaws 10. In other respects, the structure shown in Figures 6 45 and 7 is similar to that previously disclosed.

It will thus be seen that with the aid of my apparatus a submerged boat may be readily and quickly raised without the aid of a diver. This allows operations to be carried on at 50 greater depths than was possible heretofore, it being well known that human divers cannot go further than about 200 feet below the surface of the water while pontoons can go 500 feet without collapsing.

55 As a precaution against storms, I use two or more air or hydraulic cylinders, placed at each end of the pontoon diver where the submarine rises up off the mud. These cylinders are fastened to the bottom inside of the pontoon diver and push a large square girder in a slide, across under the bottom of the submarine, where it is the highest out of the mud, through another slide in the opposite side of the pontoon, so as to lift the submarine.

60 65 I claim:

1. In means for raising a submerged boat, a floating unit having means for gripping the boat in a single operation, means for lowering and raising the same, operating means for both of said means disposed outside of 70 said floating unit, and guide means for the unit supported by the same while it is floating and freeing itself automatically as the unit sinks.

2. A device for raising submerged boats 75 comprising a normally floatable unit, means for submerging the unit and for raising it, boat-gripping means carried by the unit, guide members for the unit, buoys secured to the upper ends of said members and normally 80 resting on the unit when the latter is floating, anchors suspended from the lower ends of said members and embedding themselves in the sea bottom during the initial lowering of the unit, whereupon the buoys will support said members when the unit submerges.

3. A device for raising submerged boats 85 comprising a normally floatable unit, means for submerging the unit and for raising it, boat-gripping means carried by the unit, 90 guide members for the unit, buoys secured to the upper ends of said members and normally resting on the unit when the latter is floating, anchors suspended from the lower ends of said members and embedding themselves in the sea bottom during the initial lowering of the unit, whereupon the buoys will support said members when the unit submerges, said buoys receiving varying 95 quantities of water for regulating the supporting force exerted on said members.
